UNITED STATES PATENT OFFICE.

MILTON E. BERTRAM, OF CLEVELAND, OHIO.

VALVE-OPERATING MECHANISM.

1,072,812.

Specification of Letters Patent. Patented Sept. 9, 1913.

Application filed March 4, 1912. Serial No. 681,432.

To all whom it may concern:

Be it known that I, MILTON E. BERTRAM, a citizen of the United States of America, residing at Cleveland, in the county of Cuyahoga and State of Ohio, have invented certain new and useful Improvements in Valve-Operating Mechanism; and I hereby declare the following to be a full, clear, and exact description of the invention, such as will enable others skilled in the art to which it pertains to make and use the same.

This invention relates to improvements in valve-operating mechanism, and pertains more especially to mechanism for operating a substantially vertically arranged rotary plug-valve.

One object of this invention is to positively loosen the valve relative to its seat as soon as the valve during its rotation begins to stick to said seat.

Another object is to directly rotate the valve by laterally projecting members with which a shaft arranged coincidently with the axis of the valve is provided, and to have said shaft and the valve provided with interengaging members contoured as required to unseat the valve when the valve during its rotation by the shaft begins to stick to its seat and without interfering with the freedom of the valve to unseat at any time against the action of means acting to retain the valve seated.

Another object is to avoid a spring driving connection between the shaft and the valve.

Another object is to prevent injury to the valve and valve-operating mechanism by any force or influence tending to rotate the valve in a direction opposite to the direction in which the valve is being rotated by the shaft during the operation of the shaft.

Another object is to unseat the valve during the rotation of the valve by the shaft whenever the valve begins to stick to its seat regardless of the direction in which the valve is being rotated by the shaft during the operation of the shaft.

Another object is to render the construction simple and durable, reliable in its operation, and not liable to get out of order.

With these objects in view, and to the end of attaining any other advantage hereinafter appearing, this invention consists in certain features of construction, and combinations and arrangement of parts, herein-after described, pointed out in the claims,

and illustrated in the accompanying drawings.

In said drawings, Figure 1 is an elevation, largely in central vertical section, of a valve-casing containing a plug-valve operated by mechanism embodying my invention. Fig. 2 is a horizontal section taken along the line 2—2, Fig. 1, looking upwardly. Fig. 3 is an upper end view of the valve-driving shaft. Fig. 4 is a bottom view of a spider which forms a member of the valve and participates in the formation of a cam-connection between the valve and said shaft.

Referring to said drawing, A indicates a suitably applied horizontally arranged shaft operatively provided with a bevel-gear *a* which meshes with a bevel-gear *b* operatively mounted on a suitably applied vertically arranged shaft B. A valve-casing C is arranged at the upper end of the shaft B and provided interiorly with an upwardly flaring circular chamber 10. The upwardly flaring wall 12 of the chamber 10 extends circumferentially of and forms a seat for the downwardly tapering vertically arranged normally seated rotary plug-valve D shown provided with a port 13 extending laterally through the valve.

The valve-casing C is shown provided with a fluid-receiving port 14 and a fluid-discharging port 15 arranged at the opposite sides respectively of the valve D and arranged in line endwise, and said valve has its port 13 arranged to establish communication between the ports 14 and 15 of the valve-casing during the rotation of the valve.

The valve D is operatively connected, as will hereinafter appear, with the shaft B which extends endwise of and loosely through the annular hub 16 of a spider *d* which is removably secured by screws *e* to the body of the valve. The shaft-surrounding member 16 is rigid therefore with the body of the valve and concentric relative to the axis of the shaft and forms a member of the valve. Obviously therefore the valve D is shiftable upwardly independently of the shaft B to unseat the valve, and the shaft is arranged at the lower end and coincidently with the axis of the valve. Operative connection between the valve and the shaft B is effected by a cam-connection provided between the shaft and the valve, which cam-connection is capable of producing unseating movement of the valve. Said cam-

connection comprises recesses 17 formed in and spaced circumferentially of the shaft-surrounding member 16 of the valve and engaged by laterally projecting lugs or members 18 which are formed on and spaced circumferentially of the upper portion of the shaft B. The shaft B is rotated in the one direction or the other according as the valve is to be rotated in the one or the other direction. The recesses 17 decrease in width upwardly, that is, have their side walls diverging upwardly,—and extend from the lower extremity of the shaft-surrounding member 16 of the valve substantially vertically upwardly to permit the valve to move upwardly from its seat when the shaft B is at rest and during the rotation of the shaft. Each member 18 of the shaft B is triangular and arranged between the downwardly diverging side walls of a recess 17 and has upwardly converging sides, as shown in Fig. 1, being preferably spaced at its upper end, as at 20, from the upper extremity of said recess. Hence the valve does not rest on the members 18 of the shaft but only rests on the valve-seat 12.

An externally screw-threaded head G is arranged above and opposite the upper end of the valve and screwed into the valve-casing C and therefore removably secured in place. The head G forms the upper end wall of the valve-containing chamber 18 and is larger diametrically than the upper and diametrically larger end of the valve. The valve terminates at its upper end a suitable distance below the head G to form a space between said head and said valve to permit lifting of the valve when the valve begins to stick to its seat.

During the rotation of the valve each recess 17 in the shaft-surrounding member 16 of the valve has that side wall thereof which faces opposite to the direction in which the valve is rotated engaged by a projecting member 18 of the shaft, and Figs. 1 and 2 illustrate the rotation of the valve in the direction indicated by the arrow. As soon as the valve during its rotation by the shaft B begins to stick to its seat the cam-connection formed as hereinbefore described between said shaft and the valve results in lifting the valve independently of the shaft and thereby at once loosens the valve relative to its seat.

By the construction hereinbefore described it will be observed that the valve is operatively connected with the shaft B but movable from and toward its seat when the shaft is at rest as well as during the rotation of the shaft; that the valve is directly and positively driven by the shaft B; that the valve is rotated in the one direction or the other according as said shaft is rotated in the one or the other direction; that the valve is positively unseated or loosened rela-

tive to its seat as soon as the valve during its rotation begins to stick to said seat regardless of the direction in which the valve is rotated by the shaft, and that injury to the valve and valve-operating mechanism by any force or influence tending to rotate the valve in a direction opposite to the direction in which the valve is rotated by the shaft is avoided.

To prevent the valve from being rendered too loose relative to its seat during the unseating of the valve by the cam-connection between the valve and the shaft B, an end bearing is provided for the upper and diametrically larger end face of the valve, which bearing comprises a screw H which is arranged vertically and coincidently with the axis of the valve and engages and extends through a correspondingly screw-threaded hole g formed in and centrally of the head G. The lower portion of the screw H surrounds the upper portion of a spiral spring K which is coiled around a lug or upwardly projecting member 21 formed on and centrally of the upper end of the valve D, which spring is interposed between the screw H and a metal plate L which surrounds the lug or member 21 and is spaced downwardly from the lower end of the screw H and rests on the valve. Anti-friction balls l are interposed between the under side of the plate L and the valve so as to effect the reduction to a minimum of the friction between the valve and said plate during the rotation of the valve. The spring K obviously acts to retain the valve-seated, and of course any unseating of the valve by the cam-connection between the valve and the shaft is against the action of said spring.

By the construction hereinbefore described it will be observed that the valve is free to be unseated at any time against the action of the spring K, and the spacing of the screw H upwardly from the plate L accommodates upward displacement of the valve to unseat the valve, but the space between said plate and said screw is of course less than required to lift the valve far enough to interrupt operative connection between the valve and the shaft B. Obviously the screw H forms an abutment for the upper end of the spring K, and the tension of said spring can be regulated by a manipulation of the screw or abutment, and the hereinbefore described type of cam-connection between the valve and the shaft B permits the valve to rest wholly on its seat 12 and to grind on said seat during the rotation of the valve and thereby insure a perfect seating of the valve.

What I claim is:—

1. The combination, with a shaft provided at one end with laterally projecting members which are spaced circumferen-

tially of the shaft; a normally seated valve arranged at said end and coincidently with the axis of the shaft and provided with a member which extends circumferentially of the shaft and is provided with recesses which are spaced circumferentially of the shaft and have their side walls diverging toward the opposite end of the shaft, said recesses being engaged by the aforesaid members of the shaft and arranged to permit movement of the valve from and toward its seat when the shaft is at rest and during the rotation of the shaft.

2. The combination, with a shaft provided at one end with laterally projecting members which are spaced circumferentially of the shaft and have their sides converging toward said end of the shaft; a normally seated valve arranged at said end and coincidently with the axis of the shaft and provided with a member which extends circumferentially of the shaft and is provided with recesses engaged by the aforesaid members of the shaft and arranged to permit movement of the valve from and toward its seat when the shaft is at rest and during the rotation of the shaft.

3. The combination, with an upright shaft provided at its upper end with laterally projecting members which are spaced circumferentially of the shaft and have upwardly converging sides; a normally seated downwardly tapering valve arranged at said end and coincidently with the axis of the shaft and provided at its lower end with a member which extends circumferentially of the shaft and is provided with recesses extending upwardly from the lower extremity of said member of the valve, which recesses have their side walls diverging downwardly and are engaged by the aforesaid projecting members of the shaft.

4. The combination, with an upright shaft provided at its upper end with laterally projecting members which are spaced circumferentially of the shaft and have upwardly converging sides; a normally seated downwardly tapering valve arranged at said end and coincidently with the axis of the shaft and provided at its lower end with a member which extends circumferentially of the shaft and is provided with recesses which have their side walls diverging downwardly and are engaged by the aforesaid projecting members of the shaft, said recesses extending upwardly beyond said members of the shaft and being arranged to permit upward movement of the valve independently of the shaft when the shaft is at rest and during the rotation of the shaft.

5. The combination, with a downwardly tapering rotary valve provided at its lower end with a member which extends circumferentially of and is concentric relative to the axis of the valve and has recesses spaced

circumferentially of said axis, which recesses extend substantially vertically upwardly from the lower extremity of said member of the valve and have downwardly diverging walls, and a seat for the valve, of an upright shaft arranged at the lower end and coincidently with the axis of the valve, which shaft is provided with members which are spaced circumferentially of the shaft and project laterally of the shaft into the aforesaid recesses.

6. The combination, with a downwardly tapering rotary valve provided at its lower end with a member which extends circumferentially of and is concentric relative to the axis of the valve and has recesses spaced circumferentially of said axis, which recesses extend substantially vertically upwardly and have downwardly diverging walls, and a seat for the valve, of an upright shaft arranged at the lower end and coincidently with the axis of the valve, which shaft is provided with members which are spaced circumferentially of the shaft and project laterally of the shaft into the aforesaid recesses, and said members of the shaft extending upwardly into said recesses a distance greater than the valve is movable upwardly independently of the shaft.

7. The combination, with a downwardly tapering rotary valve provided at its lower end with a member which extends circumferentially of and is concentric relative to the axis of the valve and has recesses spaced circumferentially of said axis, which recesses extend substantially vertically upwardly from the lower extremity of said member and have downwardly diverging walls, and a seat for the valve, of an upright shaft arranged at the lower end and coincidently with the axis of the valve, which shaft is provided with members which are spaced circumferentially of the shaft and project laterally of the shaft into the aforesaid recesses and have their sides converging upwardly, and means arranged above the valve and acting to retain the valve seated.

8. The combination, with a downwardly tapering rotary valve provided at its lower end with a member which extends circumferentially of and is concentric relative to the axis of the valve and has recesses spaced circumferentially of said axis, which recesses extend substantially vertically upwardly from the lower extremity of said member and have downwardly diverging walls, and a seat for the valve, of an upright shaft arranged at the lower end and coincidently with the axis of the valve, which shaft is provided with members which are spaced circumferentially of the shaft and project laterally of the shaft into the aforesaid recesses and have their sides converging upwardly, and means acting to retain the valve seated, said members of the shaft extending

upwardly into the recesses a distance greater than the valve is movable upwardly independently of the shaft.

9. The combination, with an axially tapered rotary valve and a seat for the valve, of a rotary driving member for said valve substantially co-axial therewith, means for normally holding the said valve axially to its seat and a double acting cam connection between the valve and the rotary driving member, said driving connection comprising two meshing parts one consisting of a member which extends circumferentially of and is concentric with the axis of the valve and driving member and has recesses spaced circumferentially of said axis, which recesses are substantially axial and have divergent walls, and the other of which comprises portions projecting laterally of the axis of the valve and mating with the recesses, one of said parts being carried by the valve and the other by the rotary driving member.

10. The combination, with an axially tapered rotary valve and a seat for the valve,

of a rotary driving member for said valve substantially co-axial therewith and a double acting cam connection between the valve and the rotary driving member, said driving connection comprising two meshing parts one consisting of a member which extends circumferentially of and is concentric with the axis of the valve and driving member and has recesses spaced circumferentially of said axis, which recesses are substantially axial and have divergent walls, and the other of which comprises portions projecting laterally of the axis of the valve and mating with the recesses, one of said parts being carried by the valve and the other by the rotary driving member.

11. In testimony whereof, I sign the foregoing specification, in the presence of two witnesses.

MILTON E. BERTRAM.
